AMUSEMENT GAME APPARATUS

Steven F. Kordek, Chicago, Ill., assignor to Genco, Inc.,
Chicago, Ill., a corporation of Illinois

Application May 18, 1956, Serial No. 41,540

Term of patent 14 years

(Cl. D34—5)

Fig. 1 is a perspective view of an amusement game apparatus showing my new design;

Fig. 2 is a side elevational view thereof.

The legible matter is shown in broken lines for illustrative purposes only.

The opposite side and back have substantially the same appearance respectively as the side shown in Fig. 2 and the front shown in Fig. 1.

I claim:

The ornamental design for an amusement game apparatus, as shown and described.
